UNITED STATES PATENT OFFICE.

ALBERT M. BEAN, OF COLVILLE, WASHINGTON.

PORTABLE MUSIC-SHEET CONTAINER AND TURNER.

1,344,374.

Specification of Letters Patent. Patented June 22, 1920.

Application filed October 19, 1918. Serial No. 258,817.

To all whom it may concern:

Be it known that I, ALBERT M. BEAN, a citizen of the United States, residing at Colville, in the county of Stevens and State 5 of Washington, have invented certain new and useful Improvements in Portable Music-Sheet Containers and Turners, of which the following is a specification.

My invention relates to a music leaf 10 turner.

One important object is to provide an article of this nature which is portable, may carry sheets of music flat and may be placed upon the piano or other instrument to remain in place by its own weight.

Other objects are to provide a compartment for a selective supply of music sheets; means enabling the title of the sheets to be readily read and the sheets to be readily 20 grasped; a light weight closure for the cabinet and a riser adapted to directly engage the supporting rack to mount the operating handles of the turner for free operation.

With the above and additional objects, 25 which will appear hereinafter, in view, the invention has been embodied in one preferred form as illustrated in accompanying drawings.

In said drawings:—

30 Figure 1 is a front elevation of the improved music leaf turner with the closure in open position and with one leaf of the music sheet turned;

Fig. 2 is a perspective view of the apparatus;

Fig. 3 is a cross sectional view on the line 3—3 of Fig. 2, and

Fig. 4 is a fragmentary bottom view of the apparatus.

40 In carrying out the invention, a suitable container or cabinet section A is provided, being made of wood, reinforced leather or any other suitable material and essentially having a back wall 5, a side wall 6, a top wall 7, a bottom wall 8 and a partition wall 9. As well shown in Fig. 3, a compartment is provided between the walls 5 and 9 to contain a supply of music sheets as at 10. In order that the numbers or titles of the 45 music sheets may be readily read, the wall 9 is cut away as at 11. It will be realized that the upper right hand corner of the music projects into the portion 11 as shown in Fig. 1. Portion 11, together with a cutaway in 50 portion 12, provided in top wall 7, enables

the music sheets to be readily grasped by the fingers, for removal.

As shown in the drawings, as at B, two music leaf turners are employed. It is obvious however that any preferred number 60 may be utilized. These turners may also be of any desired construction. As shown in the drawings however each comprises a main rod 13, which is journaled in a bearing sleeve 14 suitably fastened in the bottom wall 8, 65 at a portion which projects beyond and in front of the wall 9. Below the sleeves, each rod 13 is formed into a crank 15 having a manipulating handle 16. At the top, each rod 13 is bent at a right angle to provide an 70 arm 17. Spaced from each arm 17, and rigidly secured to the arms 13 in any suitable manner, is an arm 18, parallel with arm 17. A rod or wire 19, parallel with rod 13, may be rigidly connected to the arms 17 75 and 18, so that the arms 13, 17 and 18 and 19, will form a rectangular frame to engage the leaf, and one which will be substantially open so as not to interfere with the reading of the matter delineated upon the leaf. The 80 arms 13 it will be noticed are journaled at one point namely in the bearings 14. The arms 18 prevent undue downward displacement of the frames while the cranks 15 prevent undue upward displacement of the 85 frame.

The music leaf turners are so constructed that they may compactly rest against the wall 9 and each other, especially in view of the provision of an arch 20 on one of the 90 arms 18 so as to pass around the opposite rod 13, as shown in Fig. 3, and in view of the formation of the cranks 15 and their handles 16 so that the right hand crank shown in Fig. 1 will not be engaged or interfered with by the left hand crank of Fig. 1 when it is moved into the position of Fig. 3 and Fig. 4.

The cabinet section containing the music and the turners, have enough weight to remain in the position in which it is placed upon the instrument. For instance it may be placed upon the music rack of a piano. The rack is directly engaged by a riser 21 extending from and below the bottom wall 100 8 and which mounts the cranks 15 and handles 16 in such a position as not to be interfered with by surrounding structure of the piano or other instrument.

The closure for the cabinet is designated 110

C and preferably is rather light in weight so as not to overbalance the cabinet section when open and in the position of Fig. 1. This closure may be made of any suitable material, for instance wood, or reinforced leather. It has a narrow side wall 22 pivoted by a vertical pintle at 23, to the wall 6. Said side wall 22 extends from a front wall 24, from which a wide side wall 25 also extends. Side wall 25 completely closes the open side of the cabinet, particularly the music compartment, and is adapted to be fastened in place or closed position by any suitable means and for instance by means 15 of a latch and lug arrangement as suggested at D.

The article may be conveniently carried through the provision of a suitable handle as at E, secured to the top wall 7.

20 In use, the music sheets desired are placed in the music compartment and the closure section C is secured in closed position by means of the fastening D. The article being relatively light in weight, may be conveniently carried from place to place by manual engagement with the handle E.

When used in connection with a musical instrument, for instance a piano, the device is mounted on the music rack, with the riser 30 21 resting thereon. Thereupon or previously as desired, the closure C is thrown into open position as shown in Fig. 1. Say a musical composition utilizing three sheets as a, b and c, as shown in Fig. 3 is used. The composition 35 is arranged over the turner as shown in Fig. 3, with the frame to the right in Fig. 1 between the leaves b and c and with the other frame between the leaves a and b. Thus at the proper sequence, handle 16 may 40 be turned to expose the contents of the inner surfaces of leaves a and b, after which after proper sequence, the other handle 16 may be turned to the left to expose the contents of the inner surface of the leaf c and the other surface of the sheet b. When desired, other 45 compositions from the music compartment may be substituted for the one shown in place in the drawings. When closing the apparatus, it will be understood that if one 50 of the frames is against the partition 9, the other frame may be readily moved against it or if both of the frames are to the left in Fig. 1, its handle may be turned to place both of the frames against said partition. 55 Thereupon the closure may be swung to closed position as in Fig. 2 and fastened.

Since merely the preferred embodiment of the invention has been illustrated and described, it is to be understood that changes 60 in the details of construction may be resorted to within its spirit and scope.

I claim:

1. A device of the class described having

a cabinet, said cabinet being provided with a compartment for music sheets and a second compartment, turning mechanism in the second compartment, and closure means common to both compartments. 65

2. A device of the class described having a cabinet, said cabinet having a rear wall, a partition spaced from the rear wall to provide a music cabinet, a closure means for the cabinet, and turning means utilizing said partition and closure means for support of the music sheets. 70

3. A device of the class described having a cabinet, a sheet turner carried thereby, manipulating means for the turner, a separate sheet turning means, a second sheet turning means carried by the cabinet, the second sheet turning means having an arch enabling it to fold compactly relative to the first sheet turning means, and the second sheet turning means having manipulating means shaped to avoid contact with the first manipulating means when the turning means is moved to closed position. 75

4. A device of the class described having a rod, means journaling said rod, said rod at its upper end being bent into an arm, a second arm, said second arm being fastened to the rod to provide a frame, said second arm engaging the bearing, and said rod below the bearing being formed into a crank, said second arm and crank preventing displacement. 80

5. A device of the class described having a cabinet provided with a rear wall, a partition wall spaced from the rear wall to provide a sheet compartment, a top and a bottom wall projecting beyond the partition, a sheet turning means journaled in the bottom wall and a closure for the cabinet pivoted adjacent one edge of the partition wall. 100

6. A device of the class described having a cabinet provided with a rear wall, a partition wall spaced from the rear wall to provide a sheet compartment, a side wall joining said rear wall and partition wall, top and bottom walls extending beyond the partition wall, sheet turning means journaled by the bottom wall and extending below the bottom wall, a riser extending below the bottom wall and said sheet turning means for the purpose specified, a closure having a relatively narrow side wall, said side wall being pivoted to the side wall of the cabinet, said closure having a front wall and a wide side wall, and a means to fasten said wide side wall to the cabinet. 110

In testimony whereof I have affixed my signature in the presence of two witnesses.

ALBERT M. BEAN.
